(57) **CLAIM**

The ornamental design for an electrical connector receptacle as shown and described.

DESCRIPTION

FIG. 1 is a top perspective view of an electrical connector receptacle having our design;

FIG. 2 is a bottom perspective view of the electrical connector receptacle of FIG. 1;

FIG. 3 is a front view of the electrical connector receptacle of FIG. 1;

FIG. 4 is a rear view of the electrical connector receptacle of FIG. 1;

FIG. 5 is a left side view of the electrical connector receptacle of FIG. 1;

FIG. 6 is a right side view of the electrical connector receptacle of FIG. 1;

FIG. 7 is a top view of the electrical connector receptacle of FIG. 1; and,

FIG. 8 is a bottom view of the electrical connector receptacle of FIG. 1.

All features shown in the figures in broken lines form no part of the claimed design.

1 Claim, 4 Drawing Sheets
